SELF-PROPELLED THREE-WHEELED SCOOTER

William A. Maher, Burbank, Calif.

Application February 21, 1955, Serial No. 34,602

Term of patent 3½ years

(Cl. D34—15)

Pig. 1

Pig. 2

Pig. 3

Figure 1 is a perspective view of a self-propelled three-wheeled scooter, showing my new design;

Figure 2 is a top plan view of said scooter; and

Figure 3 is a fragmentary front elevational view thereof, a portion of the handle being omitted for convenience of illustration.

I claim:

The ornamental design for a self-propelled three-wheeled scooter, substantially as shown and described.
